CUSHIONING MECHANISM

Ernest F. Mechlin, Washington, D. C., assignor
to The Symington Company, New York, N. Y.,
a corporation of Maryland

Application February 24, 1931. Serial No. 517,968

6 Claims. (Cl. 213—22)

This invention relates to railway draft rigging, and, more particularly, to an arrangement involving a plurality of cushioning means or devices so disposed that a greater drawbar travel and cushioning effect is provided for buffing forces than for draft forces.

The principal object of my invention, generally considered, is the provision of draft rigging involving a vertical yoke embracing a cushioning device, preferably comprising a friction draft gear adapted to cushion draft and buffing forces, a cushioning device, preferably in the form of a friction draft gear of smaller capacity, being disposed behind the yoke and lying in a plane at right angles to the plane of the first-mentioned cushioning device, and partially embraced by a device connecting the sills and adapted to function as a center filler casting, said last-mentioned cushioning device being adapted to provide an increased cushioning effect for the absorption of buffing shocks.

Another object of my invention is to provide a supplemental draft gear disposed between the rear end of an associated yoke and a center filler casting, said supplemental gear being of smaller vertical dimension at its rear end than at its front, whereby said rear end is adapted to be supported from the center filler casting and disposed above the bottoms of the sills with the front end extending below the bottoms of said sills and supported on a carry iron.

A further object of my invention is to provide a draft rigging involving a vertical yoke embracing a friction draft gear operable on both buff and draft, in combination with a supplemental gear disposed rearwardly of the yoke and operable only on buff, said supplemental gear being embraced by a center filler casting formed with lugs extending forwardly on either side of said gear and adapted to function as rear stop lugs for the forward gear and as means for limiting forward movement of the rear follower for said gear, which rear follower also functions as a front follower for the supplemental gear.

Other objects and advantages of the invention relating to the particular arrangement and construction of the various parts will become apparent as the description proceeds.

Referring to the drawings illustrating my invention, the scope whereof is defined by the appended claims:—

Figure 1 is a vertical longitudinal section taken between the draft or center sills of a railway vehicle and showing one embodiment of my draft rigging with associated cushioning devices or

draft gears in side elevation, portions being shown in section to more clearly illustrate the construction.

Figure 2 is a partial plan and partial horizontal sectional view showing the arrangement illustrated in Figure 1 on one side of the longitudinal center line.

Figure 3 is a fragmentary view corresponding to Figure 2, but showing how a standard yoke and friction draft gear may be substituted for the cushioning devices illustrated in Figure 2.

Figures 4 and 5 are views corresponding, respectively, to Figures 1 and 2, but showing a modification.

Figures 6, 7 and 8 are diagrams representing the cushioning effect of the main and auxiliary gears singly and in series.

Referring to the drawings in detail, like parts being designated by like reference characters, and first considering the embodiment of my invention illustrated in Figures 1, 2 and 3, there is shown a main cushioning device or friction draft gear 1, an auxiliary cushioning device or friction draft gear 2 mounted between draft or center sills 3 of an associated railway vehicle, the main or front cushioning means 1 being normally embraced by an associated vertical yoke 4. The yoke is connected to an associated drawbar or coupler 5 by means of a horizontal draft key 6 passing through registering slots 7 in the drawbar, 8 in the yoke, and having its ends received in corresponding slots 9 in cheek plates 10 and/or sills 3 of the vehicle. Said cheek plates 10 may, if desired, be rearward extensions of a striking casting and sill tie member, such as indicated at 11, in Figures 4 and 5, said casting being formed with an aperture 12 receiving the drawbar or coupler stem 5.

The intermediate portions of the sills 3, or those rearwardly of the auxiliary gear 2, are connected by a center filler or backstop member, preferably formed as a casting 13 and provided with a thimble 14 adapted to receive a king pin (not shown). The casting 13 is desirably formed with forwardly extending lug portions 15 adapted to function as rear stops for the yoke 4, and associated gear 1, and embrace the rear or auxiliary gear 2.

The main or front gear 1 desirably comprises a housing or casing 16, one end, which, in the embodiment disclosed is the front end, being open and provided with rearwardly converging faces 17 either on the casing 16 or on separable blocks 18 interlocked therewith. Said faces 17 are normally engaged by correspondingly inclined or an-

gularly positioned surfaces 19 on associated friction wedges or blocks 20, the inner ends of said blocks desirably interlocking with respect to the housing or members 18, as by having lugs or 5 shouldered portions 21 overlying corresponding portions on the housing or members 18. The friction blocks 20 are held in engagement with the housing or friction shoes 18 by resilient means such as curved plate springs 22. Release of the 10 gear is effected, in the embodiment disclosed, by curved plate release springs 23 acting on an intermediate follower 24 and divided into three groups, the groups which are concave toward one another being separated by a spacer or filler 15 plate 25. The intermediate follower 24 directly engages the inner ends of the friction wedges 20. A front follower 26 is preferably disposed between the rear end of the drawbar 5 and the front ends of the friction blocks 20, said front follower being 20 limited in forward movement by lug portions 27 desirably formed adjacent the rear ends of the cheek plates 10.

The yoke-acting means 4 which embraces the gear 1 desirably has the rear end portion 28 which 25 connects the arms 29 thereof provided with a rear face 30 which is desirably flat and of relatively great area, as illustrated, for transmitting buffering force received from the housing 16 through the associated rear follower 31 to the 30 preferably vertically aligned friction elements or wedges 32 of the rear or auxiliary gear 2. Said wedges 32 are desirably relatively movable vertically and formed with rearwardly converging friction faces 33 engaging correspondingly inclined faces 34 on the housing or friction casing 35 of the gear 2, said friction faces being desirably disposed at a sufficiently obtuse angle, 35 preferably more obtuse than that of the main gear, so that the associated curved plate springs 36 may effect release of the gear without the necessity of additional or release springs, such as used in the housing 16 of the gear 1. Said friction faces 33 and 34 are desirably supplemented by rearwardly disposed friction faces 37 40 on the wedge blocks and engaged surfaces 38 on the housing, said auxiliary surfaces being separated from the main friction surfaces by shouldered portions 39 on the wedge blocks and 40 on the housing for effecting interlocking between the 45 wedge blocks and housing for limiting outward movement of said wedge blocks.

The rear end of the yoke-acting means 4 and associated draft gear 1, the rear follower 31 and the front end of the auxiliary gear housing 35 are 50 desirably supported by a carry iron 41. The front end of the yoke and corresponding portion of the gear 1, the front follower 26 and the drawbar 5 may be supported in a similar manner and/or by the key 6. The rear draft gear housing 35 is desirably formed with its rear end of less 55 vertical height than the front end, said front and rear ends being desirably joined by rearwardly converging walls 42. Thus, the lower portion of the rear end of the housing is desirably disposed above the lower edge of the sills 3 and supported on a forwardly extending web or flange 43 60 on the center filler casting 13, a transverse wall 44 forwardly of the king pin thimble 14 normally engaging the rear face of the housing 35 and functioning as a backstop therefor.

The forwardly extending portions 15 of the center filler casting 13 and the forwardly extending underlying ledge 43 form a pocket which receives the housing 35 of the gear 2 and holds it in position with respect to the sills. The front ends of

the portions 15 which function as rear stop means for the yoke 4 and associated front gear 1 are desirably notched rearwardly of the front faces thereof, as indicated at 45, to form front stop means for the follower 31, said follower, for that purpose, being notched, as indicated at 46, to provide corresponding stop shoulders on the rearmost portion 47 thereof, which is preferably wider than the forwardly extending portion 48 which is normally disposed in engagement with the rear face of the yoke 4. The lugs or extensions 15 are desirably secured to the sills as by means of rivets 49 and made amply strong to function for the purposes above set forth.

From the foregoing, it will be seen that a relatively great amount of travel and cushioning effect is provided for the drawbar or coupler when acted on by buffering forces, that is, a movement sufficient to compress both gears 1 and 2. If the front gear has a compressive movement of $2\frac{1}{2}$ " and the auxiliary gear a similar movement, provision for 5" buffering and $2\frac{1}{2}$ " pulling movement must be effected. For this reason, the slots 9 in the cheek plates 10 and sills 3 are elongated a considerable amount which, in the present embodiment, extends rearwardly of the rear faces of the lugs 27, as shown most clearly in Figure 2.

In Figure 3 there is shown a gear 50 which is longer than the gear 1 and has been substituted for the gears 1 and 2 shown in Figures 1 and 2, a standard vertical yoke 51 having been substituted for the relatively short vertical yoke 4, but the construction otherwise being the same. In other words, the sill, backstop and cheek plate arrangement shown in Figures 1 and 2 may be 105 adapted to either accommodate a pair of gears 1 and 2 in series, as shown in Figures 1 and 2, or a standard or longer gear 50 disposed between the front follower 26 and front stop lugs 27 and the extensions 15 from the center filler casting 13 110 functioning as rear stops for the housing 52 of said gear 50, the rear end of said yoke 51 and housing 52 being desirably supported by the carry iron 41, as in Figures 1 and 2. Although the gear 50 is shown as involving friction wedges 53 held 115 in engagement with correspondingly inclined friction surfaces 54 on the housing by curved plate springs 55, coil springs 56 and an intermediate follower 57 being employed to effect release, it will be understood that other gears of 120 corresponding outside dimensions may be employed instead, if desired.

Referring now to the embodiment of my invention illustrated in Figures 4 and 5, an arrangement is there disclosed involving a main cushioning device or friction draft gear 1^a and an auxiliary cushioning device or friction draft gear 2^a mounted between draft or center sills 3^a of an associated railway vehicle, the main or front cushioning means 1^a being normally embraced by 130 an associated vertical yoke 4^a, which yoke is connected to an associated drawbar or coupler 5^a, as by means of a horizontal draft key 6^a passing through registering slots 7^a in the drawbar, 8^a in the yoke, and with its ends received in corresponding slots 9^a in the cheek plates 10^a and/or sills 3^a of the vehicle. The cheek plates in the present embodiment are shown as rearward extensions or continuations of the combined striking casting and sill tie member 11 previously referred to.

The intermediate portions of the sills 3^a rearwardly of the rear gear 2^a are connected by a center filler member 13^a, which member, as in the previous embodiment, is desirably formed 145

with forwardly extending lug portions 15^a adapted to function as rear stops for the main or front gear 1^a and embrace the rear or auxiliary gear 2^a.

The main or front gear 1^a desirably comprises a housing or casing 16^a enclosing spring and friction elements 22^a and 20^a, as in the first embodiment. A front follower 26^a is desirably disposed between the rear end of the drawbar 5^a and the front ends of the friction blocks 20^a, said front follower being limited in forward movement by lug portions 25^a desirably formed adjacent the rear ends of the cheek plates 10^a. Although the drawbar 5^a is shown as the stem of a swivel butt coupler adapted to permit horizontal angling of the coupler head about the axis of a pivot pin 58, it will be understood that I do not wish to be limited to this showing.

The yoke-acting means 4^a, which embraces the gear 1^a, desirably has its rear portion 28^a which connects the arms 27^a provided with a rear face 30^a formed flat and of relatively great area for transmitting buffing forces received from the housing 16^a through the associated rear follower 31^a to the preferably vertically aligned friction elements or wedges 32^a of the rear or auxiliary draft gear 2^a. Said wedges 32^a are desirably relatively movable vertically and formed with rearwardly converging friction faces engaging correspondingly inclined friction faces on a housing or casing 35^a, as in the previous embodiment, curved plate springs 36^a being employed to hold said friction elements in engagement with the housing.

The rear end of the yoke-acting means 4^a and associated draft gear 1^a, the rear follower 31^a and the front of the auxiliary gear 2^a are desirably supported by a carry iron 39^a, as in the previous embodiment. The front end of the yoke and corresponding portion of the gear 1^a, the drawbar 5^a and the front follower 26^a are desirably supported on a front carry iron 59. The rear draft gear housing 35^a is desirably formed with its rear end of less vertical height than its front end and supported on a forwardly extending web or plate 43^a which may be the bottom bolster cover plate. A transverse web or wall 44^a on the center filler casting 13^a functions as the backstop for the gear 2^a. As in the previous embodiment, the extensions 15^a on the center filler casting 13^a not only function as rear stop means for the front gear 1^a, but are also provided with shouldered portions 45^a functioning as front stop means for the rear follower 31^a, thereby preventing said follower from being displaced when the yoke moves forwardly under the action of draft forces. The surfaces, of the webs or flanges providing the shouldered portions 45^a, which face one another, desirably lie close to the rear portion of the yoke-acting means 4^a for guiding purposes.

Referring now to Figures 6, 7 and 8, there are shown diagrams representing the cushioning action of the shock-absorbing devices or front and rear draft gears 1 and 2 or 1^a and 2^a. Figure 6 represents particularly the cushioning effect of the front gear 1^a acting by itself, the energy absorbed in closing through a distance 9^d to a final closing resistance 4^f being represented by a triangle with a base 9^d and an altitude 4^f, the energy absorbed being 18^{ff}. Figure 7 shows a similar diagram for the other gear 2^a and shows the amount of energy absorbed by closing said gear through a distance 7^d to a final closing resistance 3^f, it being assumed that the gear 2^a has a final closing resistance of three-fourths or 75% of the closing resistance of the front gear, and that the

movement to complete closure is seven-ninths of the movement to complete closure of the front gear. For example, the front gear may have a closing movement of 2 1/4" and the rear gear a closing movement of 1 3/4", allowing a total movement of the drawbar on buff of 4". Under such circumstances, the energy absorbed by the supplemental gear would be 10 1/2^{ff}.

Figure 8 represents the action of the two gears in series or when the coupler is subjected to buffing forces, the work absorbed, when so acting, being represented by a four-sided figure roughly approximating a triangle, with a base 16^d and an altitude 4^f, the work absorbed, however, being the sum of the areas of the triangles of Figures 6 and 7, or equal to 28 1/2^{ff}, the break in what would be the hypotenuse of the triangle occurring upon complete closure of the supplemental gear 2^a, as indicated by the reference character 60, when the gear 1^a engages the auxiliary backstop means or front ends of the arms 15^a. The energy absorbed when the drawbar is subjected to draft forces is, of course, represented by the triangle of Figure 6, or that for the single gear 1^a.

From the foregoing disclosure, it will be seen that I have devised railway draft rigging and associated cushioning mechanism of such a character that on buff the drawbar acts on the front mechanism which energizes the rearwardly disposed mechanism so that the associated cushioning or shock absorbing devices act in series and the combined capacity of both is utilized. The details of the action are that the drawbar 5 or 5^a, upon moving rearwardly, pushes the front follower 26 or 26^a with it, moving the friction blocks 20 or 20^a into the gear housing 16 or 16^a compressing the front mechanism 1 or 1^a, and simultaneously effecting rearward movement of the yoke 4 or 4^a, the follower 31 or 31^a, and pushing the friction elements 32 or 32^a into the housing 35 or 35^a, whereby compression of both gears in series is effected.

On account of having the front gear arranged with its greater transverse dimension horizontal, and the rear gear arranged with its greater transverse dimension vertical, said front gear is conveniently disposed between the vertically spaced arms 27 or 27^a of the yoke and guided between the sills 3 or 3^a, while the rear gear is conveniently disposed between the forwardly disposed portions 15 or 15^a of the backstop and center filler casting 13 or 13^a, and the friction elements 32 or 32^a are acted upon through direct compressive forces on the rear follower 31 or 31^a rather than upon the application of bending forces to said follower. On draft, the cushioning mechanism of the main or front gear 1 or 1^a only is utilized. Although I have shown the front or main gear as preferably of higher cushioning capacity and in the second embodiment as having a greater amount of travel to full compression, it will be understood that I do not wish to be limited to this, as, if desired, the cushioning action and the movement to full compression of the gears may be the same, or different, as desired.

Although I have disclosed preferred embodiments of my invention, it will be understood that modifications may be made within the spirit and scope of the appended claims.

I claim:

1. In railway draft rigging, in combination with draft sills, a casting connecting said sills and having a main backstop portion and arms, serving as auxiliary backstop means, extending for-

- wardly therefrom leaving a cushioning mechanism pocket therebetween, a rear cushioning device disposed in said pocket, a front follower for said device, said arms having rearwardly facing shoulders normally engaged by said follower to hold it in position with respect to said device and limit forward movement thereof, a yoke with vertically spaced arms and a connecting portion with a rear face normally engaging said follower, 5
- 10 a front cushioning device of greater capacity than said rear cushioning device disposed between the arms of said yoke, the rear face of said cushioning device being normally disposed forwardly of the front ends of said auxiliary backstop means, a drawbar acting on said cushioning device on buff, and means connecting said drawbar and yoke for the transmission of draft forces, whereon on buff said front cushioning device is not stopped by said auxiliary backstop means until a substantial movement has taken place, so 15 that said front cushioning device and rear cushioning device act in series until the front device engages the arms of said backstop, when said front device alone serves as cushioning means for the remainder of the buffing force, while on draft only the front device is effective.
2. In railway draft rigging, in combination with draft sills, a drawbar, yoke-acting means having vertically spaced arms, front cushioning means disposed between said arms, rigid front stop means connected to said sills, means connecting said drawbar and yoke-acting means for the transmission of draft forces, a follower disposed rearwardly of said yoke-acting means, 30 means connecting said sills and provided with a main backstop portion and arms serving as backstop means for said outer cushioning means, said arms having surfaces facing one another between which the rear portion of said yoke-acting means is guided, and rearwardly facing surfaces functioning as front stop means for said follower, said arms and main backstop portion providing a cushioning mechanism pocket, rear cushioning means disposed in said pocket between said arms, 35 said front cushioning means being normally spaced from said arms a distance equivalent to the permissible compression movement of said rear cushioning means, the compression stroke of each cushioning means being limited, whereby the total compression on buff is equal to the combined compression stroke of said two means, said yoke-acting means during draft transmitting the actuating force from said drawbar to said front cushioning means only, whereby the draft stroke is limited to the permissible compression stroke 40 of said front cushioning means.
3. In railway draft rigging, in combination with draft sills, a casting connecting said sills and formed with a front face normally functioning as a main backstop portion, and a flange extending forwardly from the lower portion of said face for supportingly engaging an associated cushioning device, said casting also having arms extending forwardly from the sides thereof and connected to said sills, the forward portions of said arms having front faces adapted to function as auxil- 45
- 50 iary backstop means, a drawbar disposed between said sills, yoke-acting means having vertically spaced arms connected to said drawbar, a short cushioning device horizontally disposed between the arms of said yoke-acting means, front stops 80 for said cushioning device connected to said sills, a follower normally engaging the rear end of said yoke-acting means and another short cushioning device vertically disposed between said follower and said arms and main backstop portion of the casting, said auxiliary cushioning device comprising a housing with its rear end supported on the flange of said casting, a carrier simultaneously supporting the front end of said casting, said follower, and the rear end of said yoke, and another carrier supporting the front end of said yoke, the distance between the auxiliary backstop faces of the casting and the front stops being such that the yoke, follower, and both of said cushioning devices may be removed and replaced by a standard yoke and draft gear, the rear end of which normally engages said auxiliary backstop means for limiting rearward movement thereof. 85
4. In combination with the draft sills of a railway vehicle, a casting comprising a transversely extending portion with a forward face serving as a backstop, arms extending forwardly therefrom and connected to said sills, a cushioning device mounted between said arms and normally abutting said forward face, and a front follower for 90 said cushioning device, said casting having rearwardly facing shoulders on said arms cooperating with said follower to limit forward movement thereof. 95
5. A backstop and center filler casting comprising side webs adapted for connection to associated sills, a floor portion connecting the lower portions of said webs, and a generally vertical transverse web connecting intermediate portions thereof, completing a cushioning device pocket 110 and forming a main backstop portion, said floor portion extending out from said transverse web for the support of the rear end portion of an associated cushioning device, said side webs extending forwardly of the front edge of said floor portion 115 to embrace the cushioning device and formed with forwardly facing shoulders adapted to function as auxiliary backstop portions and rearwardly facing shoulders adapted to limit forward movement of an associated follower. 120
6. A backstop casting comprising a transversely extending wall adapted to receive buffing forces from an associated cushioning device and side portions extending forwardly from said wall, adapted for connection with associated sills, and 125 to embrace said cushioning device, the forward faces of said extensions being adapted to receive buffing shocks from associated draft rigging, shouldered portions being provided extending inwardly of said side portions adjacent the ends 130 thereof to function as means for limiting forward movement of an associated follower, and a flange portion extending forwardly from said buffing wall for the support of an associated cushioning device. 135

ERNEST F. MECHLIN.
